(57) **CLAIM**

The ornamental design for a base for cookware, as shown and described.

DESCRIPTION

FIG. 1 is a bottom perspective view of a base for cookware showing my new design therefor;

FIG. 2 is a bottom plan view thereof;

FIG. 3 is a side elevational view thereof;

FIG. 4 is a bottom perspective view of a second embodiment of my invention; and,

FIG. 5 is a bottom plan view of the second embodiment, the side being identical to FIG. 3.

Throughout the drawings, the broken lines indicate environment and form no part of the design.
